UNITED STATES PATENT OFFICE.

ERNEST W. CAMPBELL, OF PROVIDENCE, RHODE ISLAND, ASSIGNOR TO
WILLIAM H. MANCHESTER, OF SAME PLACE.

DESIGN FOR A SPOON-HANDLE.

SPECIFICATION forming part of Design No. 32,305, dated March 6, 1900.

Application filed February 7, 1900. Serial No. 4,410. Term of patent 3½ years.

To all whom it may concern:

Be it known that I, ERNEST W. CAMPBELL, a citizen of the United States, residing at Providence, in the county of Providence and State of Rhode Island, have invented and produced a certain new and original Design for the Handles of Spoons, of which the following is a specification, reference being had therein to the accompanying drawing.

The figure is a front view of a spoon-handle, showing my design.

My design is suggestive of the Dutch Renaissance and may be described with reference to the drawing, as follows:

The handle end is formed by a crest of plumes *a*, surmounting a barred helm *b*, the collar of which, *c*, overlaps the escutcheon *d*. Springing from either side of the helm are upwardly-directed plume terminations *e e* and downwardly-directed series of foliated scrolls *f* and *g*. The series *g* is inwardly-directed, with its terminals resting upon the escutcheon, while the series *f* is partly overshadowed by the outline of the escutcheon. Below the

junction of the above series are oppositely-disposed foliated scrolls *l* and *m*, embraced between an emphasized marginal plain beading *n n*, which beading continues with less prominence nearly to the spoon-bowl. The lower handle-section consists of a conventionalized portion *o* of the helm and plumes above, surmounting a cluster of leaves *s*, pendent from which is a series of hemispherical beading *v*.

It is apparent that this design is also applicable to the handles of other table utensils.

Having described my invention, what I claim as new, and desire to secure by Letters Patent, is—

The design for a spoon-handle as herein shown and described.

In testimony whereof I affix my signature in presence of two witnesses.

ERNEST W. CAMPBELL.
